UNITED STATES PATENT OFFICE.

PAUL MILLER, OF PITTSTOWN, NEW YORK, ASSIGNOR OF ONE-THIRD TO FREDERICK C. CLAESSENS, OF TROY, NEW YORK.

SPARK PLUG.

Application filed March 23, 1927. Serial No. 177,809.

The present invention relates to spark plugs, and the primary object of the invention is to provide an improved spark plug embodying features whereby an intensified spark will be created between the electrodes of the plug for insuring ignition of the explosive charge in the engine cylinder with which the plug is associated.

A further object of the invention resides in the provision of a spark plug embodying a pair or more electrodes so formed and related one to the other that when the plug is firing, a divided spark bridging the gap between the spaced electrodes will be united at one of the electrodes for reinforcing of the spark and producing an extremely hot spark.

A further object of the invention resides in the provision of a spark plug embodying a central electrode having a firing point or portion which may be readily rotated in the insulating core of the plug for exposing new firing surfaces, and which electrode when in either of its adjusted positions will present firing surfaces each being spaced an equal distance from the firing point of the grounded electrode of the plug.

A still further object of the invention resides in the provision of a spark plug of the class described which may be economically constructed, and one wherein the improved central electrode for the producing of a divided spark may be readily associated with existing types of spark plugs of knock down construction.

Other objects and advantages of the invention will be apparent during the course of the following detailed description, taken in connection with the accompanying drawing forming a part of this specification and in which drawing:

Figure 1 is a central longitudinal section through a spark plug embodying the improved features of the present invention.

Figure 2 is an end elevation of the inner end of the plug and clearly illustrating the manner in which the divided spark is produced between the electrodes of the plug.

Figure 3 is a side elevation of the inner end of the central electrode and illustrating

the specific construction and arrangement of the firing portions of the electrode.

Figure 4 is a side elevation of the inner end of the central electrode and illustrating the manner in which the firing points or portions extend to opposite sides of the longitudinal center of the electrode.

Referring to the drawing in detail, and wherein similar reference characters designate corresponding parts throughout the several views, 5 designates the metal shell of the spark plug in which is mounted an insulating core 6, and which core is retained in position by means of a packing nut 7 having threaded engagement in the outer end of the metal shell 5. The core 6 and which may be formed of any suitable insulating material is provided with a centrally disposed bore 8 having its inner end enlarged for providing a pocket 9 and forming an abutment or shoulder 10. Carried by the inner end of the metal shell 5 is a ground electrode 11 of substantially L-shape in formation and arranged with the firing point 12 thereof extending inwardly toward the axial center of the bore 8.

Rotatably and slidably fitting snugly within the bore 8, and having its terminals projecting past the inner and outer ends of the bore, is a central electrode 14 having a cylindrical stem portion 15 the outer end of which projects past the outer end of the core 6 and is threaded as at 16. Formed at the inner end of the cylindrical stem portion 15 is an annularly projecting shoulder or collar 18 which is intended to be received in the pocket 9 for limiting outward movement of the electrode 14 when properly positioned within the bore 8. Below the collar 18 is formed a firing portion 20 of special and novel formation for cooperating with the electrode 11 in a manner for producing a divided spark concentrating at the firing point 12 of the electrode 11.

This firing portion 20 and which preferably constitutes an integral part of the stem portion 15, embodies a pair or more of substantially flat tines 21 and 22 which form independent firing points for the inner end of the electrode 14. These firing tines 21

and 22 are preferably formed by flattening the inner end of the electrode 14 for providing oppositely disposed flat faces 23 and then slitting the metal from the inner end on a line with the longitudinal axis of the electrode. After splitting of the flattened portion, the firing tines 21 and 22 are arcuated longitudinally in opposite directions as clearly illustrated in Figure 4 for disposing the terminals of the tines to opposite sides of the longitudinal axis of the electrodes. Each inner or confronting edge of the tines are provided with teeth 24 and it is preferred that the teeth of one tine align with the teeth of the companion tine. These tines 21 and 22 aside from having their flat faces 23 extending away from one another toward the terminals of the tines, also have their outer edges 25 extending in diverging relation from the axial center of the electrode toward the free ends of the tines as clearly illustrated in Figure 3.

A suitable packing 26 is preferably disposed between the collar 18 and shoulder 10 for sealing the inner end of the bore 8, and after insertion of the electrode 14 into the bore 8 from the inner end of the core 6, a retaining nut 27 is threaded upon the threaded extension 16 into engagement with suitable lock washers 28 for retaining the electrode 14 in position and against rotation within the insulating core 6. A suitable terminal nut 29 may be threaded upon the outer end of the extension 16 for attachment of a suitable conductor, and this nut 29 may further serve as a locking means for the nut 27.

When the electrode 14 is properly positioned within the core 6 as illustrated in Figure 2, it will be observed that the convex surface of the tine 22 and the inner corrugated edge of the tine 21 will be disposed in confronting relation with the terminal of the firing point 12 and that the convex surface and corrugated edge are spaced equidistant from the terminal of the point 12. This equal spacing of portions of the tines 21 and 22 will produce a V-shaped spark with the individual sparks meeting at the firing point 12. By rotating the electrode 14 for a one-half turn, the convex surface of the tine 21 and the inner corrugated edge of the tine 22 will be disposed in firing relation to the firing point 12 of the electrode 11. The spacing between the terminal of the firing point 12 and the tines 21 and 22 may also be varied by the positioning of packings 26 of different thicknesses between the collar 18 and shoulder 10 for limiting outward movement of the electrode when secured in position by means of the nut 27.

From the foregoing description it will be apparent that an improved and novel type of spark plug has been provided wherein the

electrodes are so formed and so related that a divided spark unites at one of the electrodes for producing a concentrated firing spark, and one wherein the central electrode special formation is readily renewable and adjustable with respect to the grounded electrode of the plug.

Changes in detail may be made to the specific form of the invention herein shown and described, without departing from the spirit of the invention or the scope of the following claims.

I claim:

1. In a spark plug, the combination of an insulating core having a central bore, a core supporting shell carrying a ground electrode at its inner end, a central electrode fitting in said bore and having independent firing portions, provided at its inner end extending in diverging relation to one another, and means for adjusting the central electrode longitudinally of the core for adjustment of the independent firing portions toward and away from the ground electrode.

2. In a spark plug, the combination of an insulating core having a central bore, a core supporting shell carrying a ground electrode at its inner end, a central electrode including a stem portion rotatably mounted in said bore and having a divided firing portion provided at its inner end forming independent firing tines extending in divergent relation from the stem portion and curved longitudinally in opposite directions, and means for retaining the central electrode against rotation with a point on each surface of the tines spaced a like distance from a single point on the surface of the ground electrode.

3. In a spark plug, the combination of an insulating core, a core supporting shell carrying a ground electrode at its inner end, and a central electrode carried by the core having a divided inner end forming independent firing tines extending in divergent relation and oppositely curved longitudinally and each being formed with a corrugated inner edge.

4. In a spark plug, the combination of an insulating core having a central bore, a core supporting shell having a ground electrode carried by its inner end, a central electrode including a stem portion rotatably and slidably fitting in said bore and provided at its inner end with a pair of substantially flat firing portions extending in divergent relation and each provided with a corrugated inner edge, said flat firing portions also being arcuated longitudinally in opposite directions whereby when the electrode is in position in the core, one corrugated inner edge and the convex surface of the companion firing portion may be disposed equidistant from said ground electrode, and means for

retaining the central electrode against rotation and longitudinal shifting within said core.

5. A central electrode for spark plugs provided with ground electrodes at their inner ends, comprising a cylindrical stem portion having a threaded outer end and an annular collar at its inner end, and a firing portion flattened and split longitudinally

at the inner end of the stem for forming a 10 pair of substantially flat tines, said tines each having teeth formed at their inner edges and oppositely arcuated longitudinally with the terminals of the tines extending to opposite sides of the longitudinal axis of said 15 stem portion.

PAUL MILLER.
